UNITED STATES PATENT OFFICE.

HARRY SHAW, OF CHICAGO, ILLINOIS.

ADJUSTABLE STOOL OR CHAIR.

1,357,825.

Specification of Letters Patent.

Patented Nov. 2, 1920.

Application filed April 21, 1920. Serial No. 375,458.

To all whom it may concern:

Be it known that I, HARRY SHAW, a citizen of the United States, residing at Chicago, Illinois, have invented certain new and useful Improvements in Adjustable Stools or Chairs; and I do hereby declare the following to be a full, clear, and exact description of the invention, such as will enable others skilled in the art to which it appertains to make and use the same.

My invention relates to stools or chairs and in one of its general aspects aims to provide simple, strong and easily manipulated means for varying the height of the seat at the pleasure of the user. More particularly, my invention aims to provide a construction for this purpose which will freely permit the rotating of the seat, which will enable the seat to be raised to any extent within the limits of the construction by freely lifting the seat and the parts attached thereto, and in which the seat can readily be lowered to any desired extent upon the pressing of an easily reached push button. Furthermore, my invention aims to provide a construction for this purpose in which the elements for latching the stem of the seat in any desired position are cheaply constructed and easily assembled, and in which certain parts of the mechanism will readily prevent other parts from unscrewing or shifting in their operative relations.

In another aspect, my invention aims to provide a simple substitute for the cast spiders heretofore used in connection with swivel chair constructions, and to provide this substitute in such a manner that it can easily and cheaply be constructed out of bar steel, and so that it will be arranged both for unusual strength and for a desirable distribution of the strains. Still further and more detailed objects will appear from the following specification and from the accompanying drawings, in which—

Figure 1 is a perspective view of the upper portion of an adjustable stool embodying my invention.

Fig. 2 is a horizontal section through the rim at the top of the stand of the stool, taken from the lower edge of the inwardly directed flange of this ring.

Fig. 3 is a fragmentary and enlarged vertical section through supporting portions of the stool, taken along the correspondingly numbered line in Fig. 1.

Fig. 4 is a section similar to the lower

portion of Fig. 3, but taken at right angles to the latter.

Fig. 5 is an enlarged section of the lower portion of Fig. 3, taken along the correspondingly numbered line of that figure.

Fig. 6 is an enlarged perspective view showing the two portions of the sliding member which release the latching members when the seat is to be lowered.

Fig. 7 is a separate view of the spring which normally holds the latching members in their operative position.

Fig. 8 is a perspective view of one of the latching members.

While my invention may be employed with stools or chairs constructed of various materials, it is particularly applicable to a metal construction and is therefore shown in the accompanying drawings in such an embodiment. These drawings show the upper part of a stool which includes in its base or stand portion legs 1 supporting a metal ring 2, which ring desirably has an inwardly directed flange at its upper end to give it a more finished appearance. Rigidly secured to this ring, which is disposed in a substantially horizontal plane, are a pair of spanners 3, each of which has both of its ends 4 formed into feet contacting flatwise with the ring 2. These metal spanners have their opposed center portions formed into semi-cylindrical parts 5 and are desirably secured to each other at opposite sides of these semi-cylindrical portions by any suitable means, such as rivets 6.

Threaded into the cylindrical portion thus formed by the two semicylindrical center parts of the two spanners is a tube 7 which serves as a guide for the stem 8 of the seat member of the stool. This stem 8 is rigidly fastened by any suitable means (which need not here be shown) to the seat 9 of the stool, and is equipped with a series of peripheral grooves which desirably are uniformly spaced longitudinally of the stem. These grooves contract the lower and desirably longer portion of the stem to a series of stem parts 9 of considerably smaller diameter, each of which is spaced from the contracted stem part below the same by a frusto-conical part 10 surmounting a cylindrical portion 11. In other words, the grooves produce the effect of a thinner stem carrying a series of spaced enlargements which slidably fit the tube 7. The cylindrical portion of each of these enlargements has a lower squared end

affording an annular shoulder at right angles to the axis of the stem for the purpose hereafter described.

At its lower end, the tube 7 is enlarged 5 considerably in diameter to afford a relatively large and downwardly open pocket for housing the latching members of my appliance. This pocket is normally closed by a cap 12 threaded upon it and having a central aperture substantially corresponding to the bore of the sleeve 7. Within this pocket I dispose a pair of latching members 13, each of which desirably consists of a substantially arcuate casting having a groove 15 on its laterally outward face and having one end chamfered and recessed. Seated in the lateral grooves on the two latching elements 13 are the arms of a spring 14, which arms desirably are bent permanently out of alignment with each other when the spring is manufactured (as in Fig. 7) thereby affording a bend which will coöperate with the relative angular disposition of adjacent parts of the latches in preventing the spring from rotating 25 about the axis of the said vertical stem. Moreover, these latching elements have the center portions of their opposed faces curved along lines combining to afford an opening smaller than the cross section of the contracted stem portion 9 and have these inner 30 face portions flared downwardly and outwardly as shown by the representation of one of these parts in Fig. 8.

At one end, these latching members are 35 desirably so shaped as to abut against each other only along the extreme upper edges after the manner shown in Fig. 5, so that they will rock on each other about this edge point A when they are spread apart against the pressure of the spring 14 or are forced 40 toward each other by the action of this spring. To provide for spreading them apart, I bevel each of the latching elements 13 at its other end along surfaces diverging 45 downwardly as shown in Fig. 4 and also provide the extreme upper end of the bevel portion with a recess 15 as shown in Fig. 8. These recesses in the two latching parts co-operate in affording room for the upper 50 shank portion 16 of a releasing member which also includes a plate 17 disposed between the said beveled ends and adapted to spread the latter when the said plate is moved vertically upward. The resulting 55 cam action will be evident from Fig. 4, which figure also shows that the same cam effect due to the beveling of the latching ends will coöperate with gravity and with the contractile pressure of the spring 14 in 60 normally returning the spreader plate 17 to its position of Fig. 4. To move the spreader plate upward I provide means accessible from outside the casing in which the latching elements are housed, as for example by 65 providing a shank 18 threaded into the plate

17 and carrying a push button 19 at its lower end. This shank 18 extends through a suitable aperture in the cap 12, while the shank 16 projects through a corresponding aperture in the annular flange which connects the 70 enlarged bottom end of the guide sleeve to the main portion of the latter.

With the parts thus arranged, it will be obvious from Fig. 3 that the latching members rest slidably upon the bottom of the 75 cap 12 which is supported by the guide sleeve 7 in a stationary position; also, that the spring 14 will normally approach these latching elements to cause their upper faces to underhang one of the shoulders 20 on the 80 stem of the seat member. Consequently, this stem is normally supported by the latching members, although free to rotate about its own axis. On lifting the seat, the stem is raised with it, whereupon the engagement 85 of the frusto-conical or tapering stem portions 10 with the beveled inner faces 21 of the latching members spreads the latter apart and permits the stem to be raised as much as desired. Then on releasing the hold 90 on the seat, the spring 14 snaps the latching members back into the nearest groove of the stem, thereby renewing its support of the latter in the new position.

If the seat is to be lowered, it can readily 95 be held by one hand against too sudden a descent, while the releasing member is lifted by an upward pressure on the button 19. This spreads the latching elements against the action of the spring, as shown by dotted 100 lines in Fig. 5, thereby permitting the enlargements on the stem to clear the latching members until the seat has been lowered to the desired extent. The upward pressure on the button 19 is then released, whereupon 105 the cam action of the beveled ends of the latching elements coöperates with gravity in returning the releasing stem to its normal position of Figs. 3 and 4, while the spring 110 14 causes the latching members to approach 110 each other and underhang one of the shoulders 20 on the stem of the seat member.

In practice, such a lowering of the seat to any desired extent can be effected almost instantly, particularly as the lifting of the 115 button 19 is an exceedingly simple operation. Moreover, since the guide tube 7 is stationary while the shank 16 of the releasing member extends through a perforation in the enlargement of this tube, and since 120 the extension 18 to this shank is threadedly connected with the latter and extends through a perforation in the cap 12, this releasing member also serves to prevent the cap 12 from unscrewing. Likewise, by making the button 19 of an incomplete circular form having one edge cut away and adapted to come close to the enlargements on the stem, I dispose this button so that it will 125 engage the stem in case of any rotational 130

tendency thereof, and therefore prevent it from accidentally unscrewing, it being screwed into position originally while the stem is drawn up entirely into the guide 5 tube.

By using the two latching elements of such an arcuate form as to combine in corresponding jointly to an incomplete ring approaching the bore of the enlargement on 10 the guide tube I am able to provide a considerable range of opening movement for these elements, while also permitting them to afford a bearing of considerable size for the adjacent shoulder on the stem which is 15 immediately above the latches. I can therefore employ my construction without using a guide tube enlargement of a clumsy size or highly expensive construction. Moreover, the spreader plate 17 automatically 20 prevents the latching elements from rotating within their housing, so that I do not require any special formations for this purpose, nor do I require any pivot pins or the like in connection with these latching elements. 25

To secure a good bracing effect for the spanners 3 while also distributing the connections from them to the ring 2 with uniformity, I desirably turn the feet on both 30 ends of each spanner in the same direction circumferentially of the ring 2, and desirably space the fastening rivets 22 at four equidistant points along this ring. However, I do not wish to be limited to these 35 or other details of the construction and arrangement here disclosed, it being obvious that the same might be modified in many ways without departing from the spirit of my invention.

40 I claim as my invention:

1. In an adjustable stool or chair, a supporting member including a vertical tube, a seat member including a multi-shouldered stem extending through the said tube, a pair 45 of arcuate latches mounted in the tube and movable laterally of the tube into and out of engagement with an adjacent shoulder on said stem, spring means continuously urging the latches into such engagement, and single digitally operable means for 50 moving the latches out of such engagement and for preventing a rotation of the latches about the stem.

2. A stool or chair as per claim 1, with 55 coöperating formations on the spring means and the latches for holding the former in operative position.

3. In a stool or chair, a supporting member having a vertical tube enlarged at its 60 lower end, a perforated cap threaded on the said end of the tube, a seat member including a multi-shouldered stem extending through the said tube, latching means within the enlarged end of the tube for engaging 65 with a shoulder of the stem, and single

means for releasing the latching means and for preventing the cap from unscrewing.

4. A stool or chair as per claim 3, in which the said single means comprise a vertically 70 slideable member having an enlargement engaging the latching means and having a digitally operable head.

5. A stool or chair as per claim 3, in which the latching means include a pair of relatively movable members having opposed 75 diverging ends, and in which the said single means comprises a slideable stem having an enlargement engaging the said diverging ends and adapted to force these ends apart upon a slideable movement of the stem. 80

6. Means for supporting the multi-shouldered vertical stem of a stool or chair, comprising a tube through which the stem extends, the tube having at its lower end an enlargement connected to the main part of 85 the tube by a horizontal collar, a perforate cap threaded on the lower end of the said enlargement, latching means supported by the cap for engaging an adjacent shoulder on the stem, and means extending slideably 90 through aligned perforations in the said collar and cap for releasing the latching means.

7. A stool or chair support as per claim 6, in which the said slideable means comprise two elements threaded into one another and 95 in which one of these elements is kept from rotating by engagement with the bore of the said enlargement.

8. A stool or chair support as per claim 6, in which the shoulder-engaging means are 100 freely movable on the cap and are retained in operative position by the slideable means.

9. In a stool or chair having a stem depending vertically from the seat thereof, a supporting member including an upper horizontal ring, a pair of spanners each secured at both of its ends to the ring, a vertical tube clamped at its upper end between the spanners, and means carried by the tube at the lower end thereof for engaging the stem 105 to support the latter. 110

10. In a stool or chair having a stem depending vertically from the seat thereof, a supporting member including an upper ring, a pair of spanners each secured at both ends 115 to the ring, the said spanners having medially thereof opposed semi-cylindrical portions, a tube threaded at its upper end into the cylinder formed by the said opposed portions, and means carried by the tube for 120 engaging the said stem to support the latter.

11. A stool or chair construction as per claim 9, in which each of the spanners comprises a pair of legs connected by a short semi-cylindrical portion, the legs extending 125 substantially at right angles to each other and the two spanners being secured to each other substantially at the junctures of their legs with their arcuate portions.

12. A stool or chair construction as per 130

claim 9, in which each of the spanners comprises a pair of legs connected by a short semi-cylindrical portion, the legs extending substantially at right angles to each other, 5 the two spanners being secured to each other at opposite ends of their semi-cylindrical portions, and all of the legs having feet secured to the said ring and extending in the same direction circumferentially of 10 the latter.

13. A stool or chair construction as per claim 9, in which each of the spanners comprises a pair of legs connected by a short semi-cylindrical portion, the legs extending 15 substantially at right angles to each other the two spanners being secured to each other substantially at opposite ends of their semi-cylindrical portions and the tube being threaded into the cylinder formed jointly by 20 the semi-cylindrical portions of the two spanners.

14. The combination with a chair or stool seat having a depending multi-grooved stem, of a supporting member including an in- 25 wardly flanged collar through which the

said stem extends; a pair of arcuate latches housed by the collar and supported by a flange thereof and movable from positions in which both enter one of the grooves on the stem to positions in which they are separated sufficiently to clear the stem, the latches abutting against each other at one end and having their other ends beveled on converging planes; releasing means extending through the collar substantially parallel 30 to the stem and engaging the said beveled ends, and spring means continuously urging the latches toward the stem.

15. A stool or chair construction as per claim 14, in which each latch is grooved on 40 its outer face, and in which the spring is bifurcated and has its arms seated respectively in the grooves of the two latches and converging from each other at their junction, whereby the said converging prevents 45 the spring from moving peripherally of the latches.

Signed at Chicago, Illinois, April 17th, 1920.

HARRY SHAW.
